UNITED STATES PATENT OFFICE.

EDWARD LUDDEN, OF BALTA, NORTH DAKOTA.

MACHINE FOR PACKING BUTTER AND SIMILAR MATERIAL.

1,175,157.

Specification of Letters Patent. Patented Mar. 14, 1916.

Application filed July 27, 1915. Serial No. 42,161.

To all whom it may concern:

Be it known that I, EDWARD LUDDEN, a citizen of the United States, residing in Balta, in the county of Pierce and State of 5 North Dakota, have invented certain new and useful Improvements in Machines for Packing Butter and Similar Material, of which the following is a specification.

The object of this invention is to provide 10 a machine for packing butter and similar substances which is simple in construction and which will efficiently pack the butter in such manner that it shall be uniformly distributed and evenly pressed and leveled 15 in its container.

When the butter is packed in tubs or 20 firkins which are of larger diameter at the top than at bottom and where rotary blades are employed to perform the packing operation the butter is made to rise at the sides 25 of the container more than in the middle portion thereof, thus producing a concave uneven surface at the top of the mass which is objectionable.

According to my invention I provide 30 means whereby the packers are made to rise and assume a level or horizontal position when the container is nearly full whereby a smooth and even condition is given to the mass on its upper surface.

In the accompanying drawings, Figure 1 is a view partly in front elevation and partly in section of a machine for packing butter embodying my improvements. Fig. 35 2 shows a transverse section thereof on the line 2—2 of Fig. 1. Fig. 3 is a perspective view showing particularly how the packing blades are connected and supported.

A tubular casing A is held by bolts *a* to a 40 frame B which may be attached by brackets C or otherwise to a suitable support such as the ceiling of a cellar. A rotary hollow shaft D is mounted to rotate and to slide vertically within the casing and to it is connected a horizontally arranged beveled, 45 toothed wheel E which is driven by a pinion F on a shaft *f* mounted on a bearing *g* of a hanging bracket G. The toothed wheel E is held in place against the lower end of 50 the tube A by a collar H supported by a hanging bracket *h*. It will be observed that the hollow shaft D is formed with a vertical slot *d* into which a lug *e* on the wheel E projects, so that the shaft is free to move 55 vertically to a sufficient extent relatively to

the toothed wheel. A coiled spring I within the casing A bears on top of the shaft D and tends to force it downward. Its upper end enters a cap *i* which is held in place by screws J extending through nuts *j* in the 60 frame B. By adjusting the screws the tension of the spring may be varied. The packers K are in the form of segmental blades which overlap each other as shown in Fig. 3 and together form a continuous circular packer. At its inner end each packer is hinged to the lower end of the tubular shaft D by any suitable device such as that indicated at *k*, and the packers are all connected intermediate their inner and outer 65 ends to a horizontally arranged ring L which is in turn connected to the lower ends of rods M which extend through slots *d'* in the shaft D and at their upper ends connect with the lower end of a vertical shaft N, 70 which extends up through an opening *n* in the spring cap *i*. The upper end of the rod N connects with a screw O extending through a nut *o* in the frame B. The screw O is provided with a hand wheel O' by 75 means of which the screw may be operated to raise and lower the rod N and thus raise and lower the inner or upper ends of the rods M which are pivotally connected with the rod N in the manner shown.

In operation the packers are lowered into a receptacle X containing the material to be packed and the rod N is raised or lowered to the proper extent to hold the packers at the desired angle to allow them to be 80 lowered to the lower portion of the container which lower portion is of relatively small diameter. A rotary motion is then given to the tubular shaft D by the mechanism before described and the material is 85 properly packed in the lower portion of the container. More material such as butter is then added and the packing operation is proceeded with. During the operation the material tends to rise higher at the sides 90 of the container than in the middle portion thereof but this is resisted by the packers and the pressure is transferred to the central portion thereof which is forced upward 95 against the force of the spring I and finally 100 assumes a substantially horizontal or level condition so as to give a smooth and level upper surface to the material. It will be 105 understood that when the packers are thus moved the upper ends of the rods M re- 110

main in the same horizontal plane while moving about their pivotal connection with the rod N.

The form and number of the packers 5 may be varied. I have shown a plurality of segmental members overlapping each other, but a less number may be employed with spaces between them. When overlapping packers are employed they should be 10 so set that they will rise up over the butter or other material, force it under them and thus pack it.

The machine is preferably run at about twenty revolutions per minute.

15 The opening *n* in the spring cap *i* is sufficiently large to allow the upper end *n'* of the rod N to pass through it and the screw is of sufficient length to afford a wide range of adjustment for the upper ends of the 20 rods M which control the angle of the packers. The spring I can have its tension conveniently regulated by the screw rods J which engage the cap *i*.

I claim as my invention:

25 1. A machine for packing butter and similar material, comprising a packer, a vertically movable rotary shaft to which the packer is hinged at its inner end and with which it rotates, rods pivotally connected 30 with the packer intermediate its inner and outer ends, a support to which the upper ends of the rods are pivoted, and a spring resisting the upward movement of said rotary shaft.

35 2. A machine for packing butter and sim-

ilar material, comprising a sectional packer, a vertically movable rotary shaft to the lower end of which the packer sections are hinged at their inner ends, rods pivotally connected with the packer sections intermediate their inner and outer ends, an adjustable support to which the upper ends of the rods are pivoted, and a spring resisting the upward movement of the said rotary shaft. 40

45

3. A machine for packing butter and similar material, comprising a packer, a vertically movable rotary shaft to which it is hinged at its inner end, inclined rods pivotally connected with the packer, a vertical 50 rod to which the upper ends of said inclined rods are pivotally connected, and means for adjusting said rod vertically.

4. A machine for packing butter and similar material, comprising a packer, a vertically movable rotary hollow shaft to which it is hinged, a tubular casing in which said shaft moves vertically, means for rotating said shaft, a spring within said casing exerting a downward pressure on said hollow 60 shaft, a vertically adjustable rod within said shaft, and connections between said rod and the packer.

In testimony, whereof, I have hereunto subscribed my name.

EDWARD LUDDEN.
